BOAT

Peter A. Lea, New Orleans, La., assignor of
one-ninth to George V. Demarest

Application January 13, 1942, Serial No. 426,624

5 Claims. (Cl. 115—39)

This invention relates to boats.

An object of the invention is the provision of a boat in which a plurality of propellers together with casings and bearing shafts for the propellers are removably mounted in housings which extend upwardly within the boat to a point which is above the water level so that when necessary or desired the propeller together with its casing and shaft may be removed and repaired without necessitating the placing of the boat in a dock.

Another object of the invention is the provision of a boat which has a plurality of openings in the bottom thereof with a keel extending longitudinally from the bottom of the boat with removably mounted propellers and shafting projecting through the openings and extending into power tubes supported at each side of the keel with housings projecting upwardly from the openings within the boat and above the water level so that the propellers and shafting may be removed when desired and replaced with a closure carried by the shafting and supporting casing which is adapted to be removably secured to the bottom of the housing for closing the openings.

A further object of the invention is the provision of a boat having a plurality of openings in the bottom with power tubes located at spaced intervals along the bottom of the boat in which propellers, the operating shafts for the propellers and casings which carry bearings for the shaft may be readily withdrawn through housings which extend upwardly from the bottom of the boat, located within the boat and terminate at a point above the bottom which is above the water level so that any of the propellers and shafting may be withdrawn from the housing without disturbing the operation of the boat, said propellers and power tubes being located at various horizontal levels along a longitudinal keel which projects downwardly from the bottom of the boat.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Figure 1 is a longitudinal side view of a boat

constructed according to the principles of my invention.

Figure 2 is a plan view of the same.

Figure 3 is an enlarged fragmentary vertical section, partly in elevation showing one of the propulsion units.

Figure 4 is a front end view of the boat.

Figure 5 is a fragmentary view in perspective of a removable unit which includes a propeller and operating shaft for the propeller.

Referring more particularly to the drawings 10 designates a hull having a flat bottom 11 with inclined side walls 12 and 13. The front of the boat as shown at 14, is inclined upwardly to a deck portion 15 which is horizontally disposed at the bow of the boat.

The bow of the boat above the deck portion 15 as shown at 16, is curved rearwardly and is cutter-shaped to facilitate the forward movement of the boat. The portion 16 blends into the inclined side walls 12 and 13 of the hull.

A keel generally designated by the numeral 20, is secured to the bottom of the boat and extends downwardly along the longitudinal center line 25 of the bottom for substantially the full length of the boat. The forward portion of the keel as shown at 21 is inclined upwardly and is connected to the inclined portion 14 of the bottom of the boat at the bow. One portion of the keel 30 is provided with an opening 22 for a purpose which will be presently explained. This opening is located midway of the length of the keel.

As shown more particularly in Fig. 3, the bottom 11 of the boat is provided with a plurality of openings 25. A housing 26 extends upwardly from the bottom and has a flanged portion 27 secured at 28 to the bottom in embracing relation with the opening 25 so that if the opening 25 were not closed the water would extend upwardly into the housing to a point indicated by 29. The upper end of the housing 26 as shown at 30 is open and this open end extends above the water level.

A pair of power tubes 31 and 32 are secured 45 by means of brackets 33 to the side walls of the keel 20. These tubes may have a reinforced support extending downwardly from the bottom of the boat if desired. These tubes extend from a point adjacent the bow of the boat and terminate rearwardly some distance from the transverse center of the hull as shown at 34. Each of these tubes are provided with a plurality of openings 36 and these openings are aligned with the openings 25.

A propeller 37 is located in each tube 31 and

32 in line with the openings 36 therein. These propellers are supported by a shaft 38 which is mounted in a journal 39 carried at the lower end of a casing 40 which extends downwardly through the openings 36 and carries a curved cover plate 40a which rests upon the upper end of the tube in closing relation with the opening 36.

Each casing 40 has a cover 41 rigidly secured thereto at its upper end and this cover is bolted as shown at 42 to the annular flange 27 at the lower end of the housing 26 for sealing the bottom of the housing against the admission of water when the propeller and the casing 40 is in an operative position within its respective tube 31 and 32. A boss 43 extends upwardly from the cover 41 and has bearings therein for a shaft 44 which is operatively connected at its lower end with the shaft 38. The shaft extends upwardly and projects slightly beyond the upper end 30 of each housing 26.

A separate means is provided for operating each shaft 44 although a single shaft which is operated by a motor may have operative connections with the plurality of shafts 44 projecting above the housings 26 within the boat. However, a motor generally designated by the numeral 45 is shown as a tandem type which operates a crank shaft 46 carried by a crank case 47. The crank case is connected by means of brackets 48 with a spider generally designated by the numeral 49 which has a plurality of arms 50 extending over the upper periphery of the housing 26 with flanges 51 extending downwardly from the outer end of the arms and engaging the outer wall of the housing 26. This spider may be secured in any approved manner to the upper end of the housing.

Projecting downwardly from the crank case is a bearing 52 in which is journaled a connecting socket 53 for receiving the squared end 54 of the upper end of the shaft 44. It will be seen by this construction that when the motor 45 is placed on top of a housing 26 the squared end 44 will be received by the socket 53 so that when the motor is operated the shaft 44 will be revolved.

It will be noted from this construction that in each of the housings 26 shown in Figs. 1 and 2, is located a removable unit which includes the propeller 37, the casing 40, the cover 41 and shaft 44, so that when the bolts 42 are removed this unit may be withdrawn from the tubes 31 or 32 and from the housing 26 after the motor and its supports have been removed from the upper end 30 of said housing. The cover plate 40a which is formed integrally with the casing 40 is likewise removed through the opening. However it will be necessary to turn the shaft 44 so that the blades of the propeller 37 will be in vertical alignment with the shaft 44 whereby the propeller may be readily withdrawn through the openings 36 and 25.

The housings 55 shown in Figs. 1 and 2 also contain all of the elements shown in Fig. 3 and therefore the same reference numerals are applied to the various parts forming the removable units. However, the shaft 44 and casings 40 have been shortened in view of the fact that the tubes 56 and 56a which house the propellers 37a are secured to the bottom 11 of the boat and on each side of the keel adjacent the elongated opening 22 in said keel.

A third group of housings 57 are disposed adjacent the rear of the boat and at opposite sides

of the keel 20 above power tubes 58, which receive propellers 37b. Similarly arranged units like those found in housings 26 are also located in the housings 57.

5 This construction is such that when it is necessary to remove a unit carrying a propeller from its operative position it is only necessary to raise the motor 45 from the upper end of the housing 26, 55 or 57 after the bolts 42 have been loosened or removed. If it is possible to repair the injured propeller or its connections in a boat this may be done and then reinserted in position. If it is not possible however to repair the injured part the boat will be driven by the numerous other propellers which are operating in their power tubes 31, 56 and 58 so that the boat may be propelled through the water without requiring dry-docking of the boat for repairs.

20 In view of the fact that all of the housings 26, 55 and 57 extend above the water level, water will not enter the boat. Furthermore, caps may be employed which can be placed over the top of the housings when the boat is being propelled through the water and when one of the units has been removed in order to prevent any water from entering the boat through the openings 25 and the upper ends of the housings.

25 An elongated opening 59 is formed in the keel 20 adjacent the propellers 37b and their enclosing power tubes 58 to provide for the free flow of water at this point.

30 A cutter shell 60 encloses the power tubes 31 and 32 and also the adjacent portion of the keel in order to aid in guiding the water directly through said power tubes.

35 In the drawings (Figs. 1 and 2) only one of the motors generally designated by the numeral 45 is shown but a separate motor as illustrated in Fig. 3 is attached to each of the vertical shafts.

I claim:

1. A boat comprising a hull, the bottom thereof having a plurality of openings, a housing surrounding each opening, sealed to the bottom and rising therefrom to a point above the water level, a vertical shaft in each housing, a cover removably secured to the bottom of each housing and provided with bearings for the shaft, a casing depending from the cover, the shaft projecting below the lower end of the casing, a propeller operatively connected to the shaft beyond the lower end of the casing, and a tube provided with a plurality of openings through which the propellers are inserted for operation in said tube, the tube extending longitudinally of and connected to the bottom of the boat, each casing and associated cover, shaft and propeller being removable upwardly as a unit from the boat.

2. A boat comprising a hull, the bottom thereof having an opening, a housing sealed to the bottom in line with the opening and extending upwardly to a point above the water level, a casing projecting through the lower end of the housing and having a cover removably secured to said end, said casing being secured to the cover, a shaft having bearings in the casing and projecting upwardly through the housing and downwardly below the lower end of the casing, a propeller at the lower end of said shaft, means operatively connecting the propeller to the shaft, a tube carried longitudinally from the bottom of the boat and provided with an opening through which the propeller is inserted so that the pro-

peller will operate in the tube, and means for rotating the shaft at the upper end of the housing, said shaft, cover, propeller and casing being removable upwardly as a unit from the housing.

3. A boat comprising a hull, the bottom thereof having an opening, a housing sealed to the bottom in line with the opening and extending upwardly to a point above the water level, a casing projecting through the lower end of the housing and having a cover removably secured to said end, a shaft having bearings in the casing and projecting upwardly through the housing and downwardly below the lower end of the casing, a propeller at the lower end of said shaft, means operatively connecting the propeller to the shaft, a tube carried longitudinally from the bottom of the boat and provided with an opening through which the propeller is inserted so that the propeller will operate in the tube, a closure plate for said opening secured to the casing, and means for rotating the shaft at the upper end of the housing, said shaft, cover, closure plate, propeller and casing being removable upwardly as a unit from the housing.

4. A boat comprising a hull, a keel running lengthwise of the bottom thereof and extending downwardly therefrom, the bottom having a plurality of openings at opposite sides of the keel, a housing embracing each opening, sealed to the bottom and extending upwardly in the boat to a point which is above the water level, a casing projecting downwardly from each housing and having a closed top removably secured to the bottom of said housing, a longitudinally disposed tube secured to each side of the keel and provided with passages in vertical alinement with

the openings to receive the lower ends of the downwardly projecting casings, a vertically-disposed shaft in each casing and having bearings in said casings, a propeller adjacent the lower

5 end of each shaft and having operative connections therewith, said propellers being located within the tubes and means at the upper ends of the shafts for causing rotation thereof, said casing, shafts and propellers being removable upwardly as units from the boat.

5. A boat comprising a hull, a keel running lengthwise of the bottom thereof and extending downwardly therefrom, the bottom having a plurality of openings at opposite sides of the keel, a

15 housing embracing each opening, sealed to the bottom and extending upwardly in the boat to a point which is above the water level, a casing projecting downwardly from each housing and having a closed top removably secured to the bottom of said housing,

20 a longitudinally disposed tube secured to each side of the keel and provided with passages in vertical alinement with the openings to receive the lower ends of the downwardly projecting casings, a vertically disposed

25 shaft in each casing and having bearings in said casings, a propeller adjacent the lower end of each shaft and having operative connections therewith, a cover plate connected to each cas-

30 ing for closing the passages in the tubes, said casings, cover plates, shafts and propellers being removable upwardly as a unit from the respective housings, said propellers being located within the tubes and means at the upper ends of the shafts for causing rotation thereof.

35

PETER A. LEA.
